UNITED STATES PATENT OFFICE.

ERNEST WAUGH TUNE AND WILLIAM WILLIAMS, OF OKLAHOMA, OKLAHOMA.

TIE, COLLAR, AND BUTTON HOLDER.

1,288,298.

Specification of Letters Patent. Patented Dec. 17, 1918.

Application filed May 27, 1918. Serial No. 236,729.

To all whom it may concern:

Be it known that we, ERNEST WAUGH TUNE and WILLIAM WILLIAMS, citizens of the United States, residing in Oklahoma, in the county of Oklahoma and State of Oklahoma, have invented a new and useful article called a Tie, Collar, and Button Holder, which is specified below.

This invention relates to a device of utility incorporating means for the provision of advertising space, or spaces, and consists primarily in an arrangement simple in construction, easy of manufacture, and is cheap to make.

15 An object of the invention is to provide a device of utility, and at the same time create an advertising medium.

Other objects of the invention will further appear.

20 The figure on the sheet of drawings, accompanying and forming a part of this specification shows in perspective the essential of invention.

A metallic strand 1, such as a wire is bent 25 upon itself to form a hanging bar over which may be swung such things as neckties and like elements, and from this bar,

bended rearwardly are arms 7 from which upwardly and angularly proceed arms 5, seen in dotted lines and which converge 30 somewhat before terminating in forwardly extended hooks or bars 3, upon which any suitable article may, at will be placed.

Stabilizing the structure thus formed, is an apron 6 which is provided with angular 35 edges to meet the shape of the bars 5, and which are overturned about the bars to unite the parts and create rigidity in the structure thus formed.

Emanating from the apron, in any suitable 40 manner for instance by bending forward and upward is a trough 2 for receiving such articles as collar buttons, pins, and so forth. Holes 4 are formed for hanging the structure.

Having thus described this invention, we claim:

A support made from a single piece of wire bent to form a hanger bar and hooks, a stabilizing apron for holding the support 50 rigid, said apron having hangers, and a trough supported by the apron.

ERNEST WAUGH TUNE.
WILLIAM WILLIAMS.
